CLAIM

The ornamental design for a locker panel, as shown and described.

DESCRIPTION

FIG. 1 is a front view of my locker panel. The back view would be the same.

FIG. 2 is a side view of my locker panel. Opposite side view would be the same.

FIG. 3 is a top view of my locker panel; and,
FIG. 4 is a bottom view of my locker panel.

My locker panel is characterized by the ability of the system to be assembled inside a locker to increase the storage efficiency.
